UNITED STATES PATENT OFFICE.

JOSEF PEJCHAR, OF BROOKLYN, NEW YORK.

DESIGN FOR A RING OR THE LIKE.

Application filed September 30, 1925. Serial No. 14,982. Term of patent 14 years.

To all whom it may concern:

Be it known that I, JOSEF PEJCHAR, a citizen of the United States, and resident of the borough of Brooklyn, county of Kings, city and State of New York, have invented a new, original, and ornamental Design for a Ring or the like, of which the following is a specification, reference being had to the accompanying drawing, forming part hereof, in which—

Fig. 1 is a side view of a ring exhibiting my novel design (both sides of said ring being alike in appearance), Fig. 2 is an edge view of the ring, and Fig. 3 is an end view looking at the open end.

I claim:

The ornamental design for a ring or the like, as shown.

JOSEF PEJCHAR.
